UNITED STATES PATENT OFFICE.

HENRY L. SCHOLL, OF WATERTOWN, WISCONSIN.

DEVICE FOR TREATING GOITERS.

1,280,560.

Specification of Letters Patent.

Patented Oct. 1, 1918.

Application filed February 28, 1916. Serial No. 216,800.

To all whom it may concern:

Be it known that I, HENRY L. SCHOLL, a citizen of United States, residing at Watertown, in the county of Jefferson and State 5 of Wisconsin, have invented certain new and useful Improvements in Devices for Treating Goiters; and I do hereby declare the following to be a full, clear, and exact description of the invention, such as will enable others skilled in the art to which it 10 pertains to make and use the same.

This invention relates to appliances for treating goiter, and has for its primary object the provision of a device whereby voltaic or galvanic currents of electricity 15 adaptable for electro-therapeutic used such as the treatment of goiter, may be produced.

It is well known in the medical field that unidirectional currents, or voltaic currents, 20 have been employed effectively in the treatment of goiter and that this disease has also been successfully treated by the use of mercury, zinc and iodin compounds. In the electro-galvanic treatment of goiter a limitation 25 has been found where special electrodes with external sources are used, in that the treatment is applied intermittently for a few minutes at a time and requiring many treatments.

30 The object of this invention is to employ means for generating voltaic currents in contact with the skin, in presence of mercurous iodid and calcium chlorid, a saline or acid solution; the device consisting of a 35 chain, necklace, belt or band of ornamental appearance and of easy and comfortable application, so that the wearer can apply the treatment with minimum discomfort and inconvenience.

40 More specifically the appliance embodies two bands or strips of dissimilar metal such as copper and zinc, connected by a copper wire and making a continuous course of voltaic connections having a spacer or separator 45 insulating material such as beads of amber, glass, or compositions of similar insulating materials woven between each connection, through which the copper wire passes to make numerous voltaic connections. The

50 bands or strips become active by their edges coming in contact with the skin, which has been prepared by the application of an ointment containing suitable materials, such as a combination of mercurous iodid and 55 calcium chlorid, or a prepared saline or acid solution. The skin thus treated constitutes

the electrolytic portion of the voltaic cell, which establishes a path for the current and a mild voltaic current will thus flow.

As above stated the skin of the wearer 60 forms the electrolyte of the device, which skin is in itself slightly conductive by the presence of calcium chlorid and mercurous iodid, saline or other acid solutions. The chief purpose of the mercurous iodid is to 65 furnish materials having suitable medical properties, while the chief functions of the calcium chlorid is, due to its hygroscopic property to attract moisture, likewise with a saline or other acid solution. The calcium 70 chlorid thus combined with water furnishes the electrolyte by which the electrolytic action can be initiated. The formation of zinc iodid and zinc chlorid likewise produces compounds which are hygroscopic and attract moisture, tending to add to the conductivity of the electrolytic part of the circuit. The flow of current which is thus established exercises that well known cataphoretic effect, causing certain constituents 75 to travel through the skin in the direction of the cathode, or producing cataphoresis; thus combining suitable medicinal materials with a uni-directional current which causes these materials to pass through the skin and 80 thus become readily absorbed in the circulatory system, and by dividing the band, a necklace in the middle in such manner as to position the zinc or electropositive strip on one side of the goiter and the copper or 85 electronegative strip or band on the opposite side the electrical action between these strips or bands will permeate the goiter and a thorough treatment will result.

With the foregoing and other objects in view this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views and in which:

Figure 1 is view showing the application of the improved device for treating goiters.

Fig. 2 is a sectional view through the device and Fig. 3 is an enlarged fragmentary section through a part of the device.

Referring more particularly to the drawings, the necklace as shown comprises a plu-

rality of beads 1 which may be of any desired shape and which are constructed of insulating non-absorbative material, such as celluloid, glass, amber or the like. The beads 5 1 are strung upon a pair of wires or flexible cords 2 and 3, the ends of which are connected to suitable catch sockets 4, as shown clearly in Fig. 2 of the drawings. The catches 4 have pieces of ribbon or similar 10 material as indicated at 5 connected thereto, the two sections of which are indicated at the numeral 6. The catch or clasp structures 4 form means to confine the beads upon the cords 2 and 3 and also means for connecting the ribbons 5 to the necklace proper. The ribbons 6 are tied about the neck of the wearer to hold the necklace in place.

The clasps 4 provide means for confining the beads upon the cords and the cords 2 and 20 3 extend parallel to each other, inwardly from the clasps 4, to the points 7 where they are twisted, one about the other and bowed to form a substantially elliptical enlargement at the center of the necklace. The 25 beads 1^a are mounted upon the bowed portions of the wires or cords 2 and 3 and also upon a copper wire 8 which is bent to form an ellipse and has its ends twisted together as shown at 9.

30 Strips or bands 10 and 11 are interwoven with the beads 1^a on the bowed portions of the wires or cords 2 and 3 and upon the wire 8, as clearly shown in Fig. 2 of the drawings. The strip or band 10 is electropositive material, such as zinc, while the strip or band 11 is of electronegative material such as copper. The wire 8 is a conductor which furnishes the necessary metallic connection between the 35 bands or strips 10 and 11 to make them electro-chemically active and in use becomes a part of the metal bands.

In use, an ointment as above specified is

applied to the skin which increases the electrolytic conductivity of the skin and the necklace, band or the like is then put in place 45 with the bifurcated portion over the goiter or affected parts so that the bands or strips 10 and 11 rest against the skin; there is thus produced a series of connections or contacts for two individual bands or strips forming 50 one individual cell, the electrolytic portion of which is supplied by the skin of the wearer and the ointment placed thereon, no external source of current being required for the therapeutic effect. 55

Having thus fully described the invention what is claimed is:

1. A device as set forth consisting of a belt or necklace having a looped portion formed therein, and electrodes carried by 60 each section of the looped portion and composed of metal occupying different positions in the electro motive series a plurality of insulating beads strung upon said bifurcated portion and interwoven thereon with said 65 electrodes and a conductive wire extending through said beads and electrodes.

2. A device as set forth consisting of a belt or necklace having a looped portion formed therein, to provide spaced cords, insulating beads strung on said spaced cords a copper wire extending through said beads, a strip of electropositive material interwoven with said beads upon one of said 70 spaced cords, and a strip of electronegative 75 material interwoven with the beads upon the other of said spaced cords.

In testimony whereof I affix my signature in presence of two witnesses.

HENRY L. SCHOLL.
